(57) **CLAIM**

The ornamental design for a kickstand as shown and described.

DESCRIPTION

FIG. 1 is a front, top, right side perspective view of a kickstand showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, top, right side perspective view of the kickstand of FIG. 1 shown in an environment of use with an electronic device; and,

FIG. 9 is a front, top, right side perspective view of the kickstand of FIG. 1 shown in another environment of use with an electronic device.

Broken lines illustrate portions of the kickstand that form no part of the claimed design. Additional broken lines in FIGS. 8-9, illustrate environmental subject matter and form no part of the claimed design.

1 Claim, 9 Drawing Sheets
